UNITED STATES PATENT OFFICE.

CARL H. KNUDSEN, OF BROOKLYN, NEW YORK, ASSIGNOR TO THE KNUDSEN MOTOR CORPORATION, OF WILMINGTON, DELAWARE, A CORPORATION OF DELAWARE.

PISTON CONSTRUCTION.

Application filed July 1, 1922. Serial No. 572,263.

To all whom it may concern:

Be it known that I, CARL H. KNUDSEN, a citizen of the United States, and residing at Brooklyn, in the county of Kings and State of New York, have invented certain new and useful Improvements in Piston Constructions, of which the following is a specification, such as will enable those skilled in the art to which it appertains to make and use the same.

This invention relates to piston constructions and particularly to devices of this class designed for use in connection with internal combustion engines and the object of the invention is to provide a piston construction of the class specified, the head end portion of which is provided with a chamber closed to the interior of the piston and having ports, communicating therewith through the periphery of the piston; a further object being to subdivide the chamber of the piston by two partition walls, arranged at right angles to each other, said walls being apertured to place the subdivisions of the chamber in communication, whereby air or the like may pass into one of the subdivisions of the chamber, through a predetermined number of the ports of the piston wall, into the other division of said chamber, through the ports in said partition walls and out through the other ports in the piston wall, for the purpose of cooling the head end of the piston as well as for preheating the air, or the like, passed through the chamber; and with these and other objects in view, the invention consists in a piston construction of the class and for the purpose specified, which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:—

Fig. 1 is a longitudinal, sectional view of my improved piston with part of the construction broken away.

Fig. 2 is a transverse section on the line 2—2 of Fig. 1 and

Fig. 3 is a transverse section on the line 3—3 of Fig. 1.

My invention relates to pistons for use in connection with internal combustion engines

and particularly to oil engines, in which air under pressure is passed through the cylinders of the engine for cleaning out the same, or for producing a scavenger effect and my improved piston is designed for the purpose of passing the scavenging air through the head end, prior to its admission into the cylinder or cylinders of the engine.

In the drawing I have shown one method of carrying my invention into effect and in practice I provided a piston structure 5, which is tubular in general form, and the upper end of which is closed by a substantially conical head 6, and the periphery of the piston adjacent to the head end thereof is provided with a plurality of ring grooves 7, adapted to receive piston rings, and approximately centrally of the piston are wrist-pin bosses 8 having apertures 9 which in the construction shown are tapered and one of the apertures 9 is provided with a recess 10, and a threaded bore 11 communicating with said recess and arranged at right angles thereto. The periphery of the piston, adjacent to the lower end thereof, is provided with a ring groove 12 adapted to receive a piston ring, which acts as a wiping ring.

Above the bosses 8 the piston is provided with a transverse wall 13 which is arch shape in form in cross-section and which forms in the head end portion of the piston a closed chamber 14, divided by two partition walls 15 and 16 into separate compartments 17 and 18 at either side of the partition wall 15 and these partition walls are provided with apertures 19 and 20 respectively which form a communication between the compartments 17 and 18, and the piston wall is provided with two intake ports 21 which communicate with the compartment 18 and with two exhaust ports 22 which communicate with the compartment 17.

In the use of my improved piston, the intake ports 21 and exhaust ports 22 cooperate with corresponding ports in the cylinder in which the piston is operated and air under pressure is adapted to be passed through the cylinder ports and into the compartment 18, through the intake ports 21 of the piston upwardly over the partition wall 15 and through the aperture 19 therein and the aperture 20 in the partition wall 16 and then down into the compartment 17 and outwardly through the exhaust ports 22 and this

passage of the air through the chamber 14 in the head of the piston will operate to cool the head end portion of the piston as well as to preheat the scavenging air passed 5 therethrough.

It will also be apparent that the partition walls 15 and 16 will reinforce the head end portion of the piston and will also operate as radiating fins and will function to cause the 10 air to flow through the chamber 14 or the compartments 17 and 18 thereof in a predetermined path. It will also be understood that I am not necessarily limited to the number of intake and exhaust ports employed 15 nor to the specific form of partition wall construction herein described, and various changes therein and modifications thereof may be made within the scope of the appended claims, without departing from the 20 spirit of my invention or sacrificing its advantages.

Having fully described my invention, what I claim as new and desire to secure by Letters Patent, is:—

25 1. A piston of the class described, said piston being substantially tubular in form and provided with a closed head, a transverse arc-shaped partition wall at a predetermined distance from said head, and forming 30 a closed compartment in the head end portion of the piston, the periphery of the piston being provided adjacent to and above said partition wall with a plurality of spaced apertures opening into said compartment and 35 outwardly through the piston, and a vertical apertured partition wall subdividing said compartment and the apertures in said piston wall, the aperture of said vertical partition wall being adjacent to the head end of the piston, and another apertured partition 40 wall at right angles to said first named wall.

2. A piston of the class described, said piston being substantially tubular in form 45 and provided with a closed head, a transverse partition wall at a predetermined distance from said head, and forming a closed compartment in the head end portion of the piston, the periphery of the piston being 50 provided adjacent to and above said partition wall with a plurality of spaced apertures opening into said compartment and outwardly through the piston, and a vertical apertured partition wall subdividing said 55 compartment and the apertures in said piston wall, the aperture of said vertical partition wall being adjacent to the head end of the piston.

3. A piston of the class described, said piston being substantially tubular in form and provided with a closed head, a transverse partition wall at a predetermined distance from said head and forming a closed compartment in the head end portion of the piston, the periphery of the piston being 60 provided adjacent to and above said partition wall with a plurality of spaced apertures opening into said compartment and outwardly through the piston, a vertical apertured partition wall subdividing said compartment and the apertures in said piston wall, the aperture of said vertical partition wall being adjacent to the head end of the piston, and another apertured partition 65 wall at right angles to said first named wall.

In testimony that I claim the foregoing as my invention I have signed my name this 30th day of June, 1922.

CARL H. KNUDSEN.
